ART OF CRACKING HYDROCARBONS

Application filed June 11, 1927. Serial No. 198,247.

This invention relates to improvements in the cracking of heavier and higher boiling hydrocarbon oils, such as gas oil, for the production therefrom of lighter and lower boiling hydrocarbon oils, such as gasoline and gasoline-containing pressure distillates.

This invention relates particularly to improvements in operations in which the heavier and higher boiling hydrocarbon oils are cracked by distillation under pressure. One important purpose of the invention is improvement of the continuity of such pressure distillation operations. Another is reduction of the stresses to which the apparatus in which such operations are carried out is commonly subjected. Other improvements provided by the invention will appear as the description proceeds.

Heat is required to maintain the high temperatures used in such pressure distillation operations and also to carry out the cracking operation. This heat is commonly supplied by heat transfer through heating tubes from heating gases including hot products of combustion from a fire-box in which fuel is burned; this invention relates particularly to operations carried out in such apparatus. In order to attain maximum capacity in any particular apparatus, high rates of heat transfer through such heating tubes are usually maintained in operation, ordinarily by maintaining high temperature differentials between the heating gases passing over the heating tubes and the oil flowing through the heating tubes.

The products of the cracking reaction include, in addition to the desired lighter and lower boiling oils, asphaltic and pitch-like constituents which tend to deposit in such heating tubes, impeding heat transfer from the heating tubes to the oil flowing through them. If such deposits do form, the heating tubes are deprived of the protective effect of the oil flowing through them in absorbing heat and overheating, which may be and frequently is local, results. Such overheating tends to increase the formation and deposit of such asphaltic and pitch-like constituents, so that the result is cumulative. The formation of such carbonaceous deposits necessi-

tates the periodic shut-down of pressure stills in which such cracking operations are carried out, thus interfering with continuity of operation.

Where high rates of heat transfer are maintained, the formation of such deposits in heating tubes is particularly dangerous and objectionable. Overheating becomes severe and more dangerous, and the apparatus in which the operation is carried out is subjected to severe stresses which materially shorten its useful life. The present invention provides an improved combined operation which makes possible an increase in the useful period over which such cracking operations can be carried out, that is which improves the continuity of operation, and which assists in reducing the stresses to which the apparatus used is subjected.

According to the present invention, the burden of heat transfer through the heating tubes of the apparatus in which the operation is carried out is reduced, these heating tubes are subjected to relatively mild heating conditions, and the concentration in the charge of oil undergoing pressure distillation of constituents tending to cause objectionable deposits in the heating tubes is controlled. The concentration of such objectionable constituents in the pressure still charge is controlled in a dual manner; by circulating the charge of oil through a bed of absorbent or desulphurizing or filtering material, and by supplying raw oil to the charge and discharging pitch-laden oil or tar from the charge during operation and restricting the proportion of the total raw oil supplied to the operation that is taken off as a distillate. The burden of heat transfer through the heating tubes is reduced by returning to the operation a large part of the heat escaping from the pressure still in which the operation is carried out by heat exchange between raw oil supplied to the operation and both vapors escaping from the pressure still and pitch-laden oil or tar discharged from the pressure still. Mild heating conditions, those to which the heating tubes are subjected, are advantageously maintained by recirculating over the heating tubes in ad-

mixture with fresh hot products of combustion from the fire-box in which fuel is burned for supplying heat to the operation a portion of the heating gases which have passed over the heating tubes.

5 The invention will be further described in connection with the accompanying drawings, which illustrate, in a diagrammatic and conventional manner, in elevation and partly in 10 section with parts broken away, one form of apparatus adapted for use in carrying out the improved combined process of the present invention; it will be understood that the invention is not limited to operations carried 15 out in the specific apparatus illustrated but that this specific apparatus is shown for the purpose of illustration and as one form of apparatus which is particularly advantageous.

20 The pressure still illustrated comprises a bulk supply drum 1, a battery of heating tubes 2, and circulating connections 3, 4 and 5 including a circulating pump 6 for circulating oil from the bulk supply drum upwardly 25 through the heating tubes and back to the bulk supply drum. A bed of finely divided absorbent or filtering or desulphurizing material 7 is arranged in the bulk supply drum on a suitable support 8 adapted to retain the 30 finely divided material but to permit free passage of oil extending entirely across the path of circulation of the still charge. This support may consist, for example, of one or more screens of appropriate fineness arranged between perforated plates or gratings. Connection 9 is provided for discharging pitch-laden oil or tar during 35 operation. Connection 10 is provided for supplying cool oil to the bearings of the circulating pump 6. Connection 11 is provided for pumping out the still at the end of a run and for initially charging it at the beginning of a run. The heating tubes 2 are arranged in the heating 40 flue of a furnace 12 provided with a fire-box 13 from which hot products of combustion pass through the heating flue to a stack flue 14. A return flue 15 is provided for recirculating through the heating flue a part of the 45 heating gases escaping to the stack flue 14. This return flue is provided with suitable forcing means, such as a steam jet blower as 50 illustrated, or a fan or other blower.

55 A reflux tower 16 is arranged above the bulk supply drum 1. Vapors escaping from the bulk supply drum enter the lower end of this reflux tower through vapor line 17 and vapors remaining uncondensed escape from the upper end through vapor line 18 to a 60 condenser 19 arranged to discharge into a receiver 20. The distillate product is discharged from receiver 20 through connection 21 and uncondensed vapors and gases through connection 22. The pressure in the 65 system is maintained and regulated by means

of valve 23, or by means of suitable valves arranged beyond the condenser or receiver. Connection 24 is provided for introducing raw oil into the upper end of the reflux tower 16. Reflux condensate and admixed unvaporized raw oil from the lower end of the reflux tower into the upper end of circulating connection 3 through connection 25. Baffles, or other suitable means, are arranged in the reflux tower 16 to promote intimate contact 75 and heat exchange between oil and condensate flowing downwardly therein and vapors rising therethrough.

It will be understood that the bulk supply drum, the circulating connections 3, 4 and 5 and also the reflux tower 16 are thoroughly lagged or thermally insulated to prevent or reduce heat loss.

80 The heat exchanger 26 comprises a pair of headers 27 and 28 connected by tubes 29 extending through a shell 30. Connection 31 is provided for passing pitch-laden oil or tar discharged from the pressure still, through connection 9, through the tubes of this heat exchanger and out through connection 32. 85 By-pass connection 33 is provided in the tar line around the heat exchanges. Raw oil is circulated through the shell of this heat exchanger; in through connection 34 and out through connection 35.

90 Raw oil is supplied to the pressure still by means of either or both of pumps 36 and 37. Either or both of these pumps may be used to supply all of the raw oil introduced into the still, that introduced through the 100 reflux tower as well as that introduced directly, by means of connection 38; or the raw oil introduced through the reflux tower may be supplied by means of pump 37 independently of that introduced directly by means of 105 pump 36. A portion of the raw oil may be forced into the pressure still through the bearings of the circulating pump 6 by means of connection 10, cool raw oil being employed for this purpose, to cool and lubricate the 110 pump bearings. Raw oil preheated by passage through the heat exchanger 26 is discharged through connections 39 and 40 into circulating connection 4 or through connections 41 and 24 into the upper end of the reflux 115 tower 16. By-pass connection 42 is provided between connections 34 and 35.

120 Appropriate valves are provided in the several connections for control and regulation of the flow of oil therethrough as illustrated. The discharge of pitch-laden oil or tar from the pressure still may be controlled and regulated by means of valve 43 or by means of valve 44, more advantageously by means of valve 43. When the discharge of pitch-laden oil or tar is controlled and regulated by means of valve 43, some vaporization may take place in the heat exchanger 26 and in the connections between the pressure still and the heat exchanger, but there seems to be less tendency 130

toward stoppage of the discharge connections.

In apparatus of the type illustrated, in which the normal operating charge of the pressure still is about 10,000 gallons, the bed of finely divided material may, for example, consist of from 4 to 7 tons of fuller's earth of 15-30 mesh. Other absorbent or desulphurizing or filtering materials, such as calcined 5 bauxite or pulverized coke, are useful in carrying out the invention, but fuller's earth, or similar absorbent earths or clays, is particularly advantageous. Fuller's earth seems 10 to combine in itself valuable absorbent, filtering and desulphurizing properties which 15 coact to benefit the pressure still operation. Fuller's earth also seems to have a selective action with reference to more objectionable constituents among which certain sulphur 20 compounds seem to be important.

In carrying out the invention in a pressure still of the type illustrated, in which the normal operating charge of the pressure still is about 10,000 gallons, the still is initially 25 charged, for example with about 8,000 gallons of gas oil, and brought to operating conditions of temperature and pressure in the usual way. For the production of gasoline or a gasoline-containing pressure distillate from a gas oil character charging stock, the still may be operated under a pressure in the neighborhood of 125 pounds per square inch, for example, or higher or lower pressures may be used. Pressures up 30 to 300 pounds per square inch, or higher pressures, for example, may be used, particularly where the charging stock is of lighter character or contains a substantial proportion of kerosene character components. 35 After the still reaches operating conditions of temperature and pressure, the introduction of raw oil into the upper end of the reflux tower is begun while vapors including vapors of the desired distillate product escape into the reflux tower from the still and the introduction of raw oil is regulated to condense and reflux to the still those components of the vapors heavier and higher boiling than desired as components of the 40 distillate product. Operating under a pressure of 125 pounds per square inch for the production of gasoline, for example, the introduction of raw oil into the upper end of the reflux tower may be controlled and regulated 45 to maintain the temperature of the vapors escaping from the upper end of the tower in the neighborhood of 450° F. or at some other predetermined value. Before the concentration of asphaltic or pitch-like constituents in 50 the circulating charge of oil in the still reaches an objectionable value, that is shortly after the introduction of raw oil into the upper end of the reflux tower is begun, the discharge of pitch-laden oil or tar is started 55 and the rate at which raw oil is supplied to

the operation is increased to maintain the still charge. Part of the raw oil supplied to the operation, or in some cases all of it, is then passed in heat exchanging relation with the discharged pitch-laden oil or tar in the 70 heat exchanger and thereby preheated before introduction into the pressure still system. At this point in the operation, the rate at which distillate is taken off, the rate at which pitch-laden oil or tar is discharged and the 75 rate at which raw oil is supplied to the operation may somewhat exceed 1,000 gallons per hour, 1,500 gallons per hour and 2,500 gallons per hour, respectively. The supply 80 of raw oil and discharge of pitch-laden oil or tar may be regulated so that the proportion of the total oil supplied to the operation, including the initial charge, taken off as distillate does not exceed about 40%, 45% or 50%. The proportion taken off as distillate 85 is advantageously restricted not to exceed about 45%, although in some cases the run may be further prolonged by restricting it to about 40%, or even to a lower value. Raw oil in excess of that introduced into the upper end of the reflux tower is introduced directly into the circulating still charge. All 90 of the raw oil introduced directly into the circulating still charge is advantageously passed through the heat exchanger. 95

In this operation, a substantial part of the heat in the vapors escaping from the pressure still and in the pitch-laden oil or tar discharged from the pressure still is absorbed by the raw oil supplied to the operation and is thus returned to the operation. The heat so returned to the operation reduces the burden of heat transfer on the heating tubes. At the same time, the bed of absorbent or desulphurizing or filtering material through 100 which the still charge is circulated acts to reduce the concentration of asphaltic and pitch-like constituents in the oil flowing through the heating tubes while the concentration of asphaltic and pitch-like constituents in the circulating charge of oil is further limited by the supply of raw oil and discharge of pitch-laden oil or tar and restriction of the amount taken off as distillate. 105 Thats, although a relatively large amount of pitch-laden oil or tar may be discharged during the operation, the heat in the discharged oil or tar is largely returned to the cracking operation proper. The corresponding reduction in the amount of heat that must be transferred through the heating tubes makes possible the maintenance of milder conditions in the heating furnace without reduction of the capacity of the pressure still. 110 The maintenance of milder furnace conditions and the supply of raw oil and discharge of pitch-laden oil or tar and restriction of the amount taken off as distillate assist in 115 improving continuity of operation and the 120 125 130

maintenance of milder furnace conditions is made possible, although a relatively large amount of pitch-laden oil or tar may be discharged during operation, by returning to the operation a large part of the heat escaping from the pressure still in the vapors taken off and in the oil or tar discharged. These milder furnace conditions are advantageously maintained by recirculating a relatively large proportion of the heating gases again over the heating tubes with fresh hot products of combustion, say as high a proportion as 70% to 90% or more, for example. The improved continuity of operation makes possible an increase in production per still per day without increasing the stresses imposed on the apparatus.

In one mode of operation, cool raw oil is introduced into the upper end of the reflux tower and all of the oil preheated by heat exchange with discharged oil or tar is introduced directly into the circulating charge of oil in the still. All or part of the raw oil introduced into the upper end of the reflux tower, however, may be preheated by passage through the heat exchanger. As the quantity of raw oil passed through the heat exchanger increases, the temperature of the preheated oil decreases, and as the temperature of the raw oil introduced into the upper end of the reflux tower increases, an increasing amount may be introduced without increasing the refluxing effected in the tower. In some cases, accordingly, all of the raw oil introduced into the upper end of the reflux tower may be preheated. Excepting that supplied to the bearings of the circulating pump, all of the raw oil supplied to the operation may be preheated and introduced into the upper end of the reflux tower, or if the refluxing action is too great part of the preheated raw oil may be supplied directly to the circulating still charge. To increase the refluxing action, part of the preheated raw oil may be supplied directly to the circulating still charge and a part of the raw oil supplied to the refluxing operation cool without heat exchange with discharged oil or tar. It is particularly advantageous to introduce the raw oil into direct contact with the vapors in the refluxing operation where it is preheated or partly preheated; the heat exchange between the vapors in the refluxing operation and the raw oil supplied thereto may however be indirect.

We claim:

1. An improved method of cracking hydrocarbon oils, which comprises circulating a charge of oil in a pressure still from a bulk supply drum through heating tubes and back to the bulk supply drum and heating it to a cracking temperature in the heating tubes, maintaining a bed of finely divided solid material extending entirely across the path of the circulating charge of oil in the bulk supply

drum, taking off vapors from the bulk supply drum under pressure and subjecting them to a refluxing operation, introducing raw oil into the vapors in the refluxing operation and returning reflux therefrom together with admixed unvaporized raw oil to the circulating charge of oil, discharging pitch-laden oil from the circulating charge of oil and preheating raw oil by heat exchange therewith, and supplying raw oil so preheated directly to the circulating charge of oil.

2. An improved method of cracking hydrocarbon oils, which comprises circulating a charge of oil in a pressure still from a bulk supply drum through heating tubes and back to the bulk supply drum and heating it to a cracking temperature in the heating tubes, maintaining a bed of finely divided solid material extending entirely across the path of the circulating charge of oil in the bulk supply drum, taking off vapors from the bulk supply drum under pressure and subjecting them to a refluxing operation, discharging pitch-laden oil from the circulating charge of oil and preheating raw oil by heat exchange therewith, and supplying raw oil so preheated in part directly to the circulating charge of oil and in part to the refluxing operation, and returning reflux from the refluxing operation together with raw oil supplied thereto to the circulating charge of oil.

3. An improved method of cracking hydrocarbon oils, which comprises circulating a charge of oil in a pressure still from a bulk supply drum through heating tubes and back to the bulk supply drum and heating it to a cracking temperature in the heating tubes, maintaining a bed of finely divided solid material extending entirely across the path of the circulating charge of oil in the bulk supply drum, taking off vapors from the bulk supply drum under pressure and subjecting them to a refluxing operation, discharging pitch-laden oil from the circulating charge of oil and preheating raw oil by heat exchange therewith, supplying raw oil so preheated in part directly to the circulating charge of oil and in part to the refluxing operation, supplying additional cool raw oil to the refluxing operation, and returning reflux from the refluxing operation together with raw oil supplied thereto to the circulating charge of oil.

4. An improved method of cracking hydrocarbon oils, which comprises circulating a charge of oil in a pressure still from a bulk supply drum through heating tubes and back to the bulk supply drum and heating it to a cracking temperature in the heating tubes, maintaining a bed of finely divided solid material extending entirely across the path of the circulating charge of oil in the bulk supply drum, taking off vapors from the bulk supply drum under pressure and subjecting them to a refluxing operation, discharging pitch-laden oil from the circulating charge of oil

oil and preheating raw oil by heat exchange therewith, supplying raw oil so preheated directly to the circulating charge of oil, supplying cool raw oil to the refluxing operation, 5 and returning reflux from the refluxing operation together with raw oil supplied thereto to the circulating charge of oil.

5. An improved method of cracking hydrocarbon oils, which comprises circulating a 10 charge of oil in a pressure still from a bulk supply drum through heating tubes and back to the bulk supply drum and heating it to a cracking temperature in the heating tubes, maintaining a bed of finely divided solid material extending entirely across the path of the circulating charge of oil in the bulk supply drum, taking off vapors from the bulk supply drum under pressure and subjecting them to a refluxing operation, supplying raw 15 oil to the refluxing operation and returning reflux therefrom together with raw oil supplied thereto to the circulating charge of oil, discharging pitch-laden oil from the circulating charge of oil, supplying raw oil directly 20 to the circulating charge of oil and preheating all of the raw oil so supplied directly to the circulating charge of oil by heat exchange with pitch-laden oil discharged therefrom.

6. An improved method of cracking hydrocarbon oils, which comprises circulating a 25 charge of oil in a pressure still from a bulk supply drum through heating tubes and back to the bulk supply drum and heating it to a cracking temperature in the heating tubes, maintaining a bed of finely divided solid material extending entirely across the path of the circulating charge of oil in the bulk supply drum, taking off vapors from the bulk supply drum under 30 pressure, discharging pitch-laden oil from the circulating charge of oil in sufficient quantity to maintain said charge of oil substantially constant, supplying to the circulating charge of oil raw oil preheated by 35 heat exchange with vapors taken off from the bulk supply drum and with discharged pitch-laden oil, and restricting the amount taken off as distillate not to exceed about 45% of the total raw oil supplied to the 40 pressure still including the initial charge.

7. An improved method of cracking hydrocarbon oils, which comprises circulating a 45 charge of oil in a pressure still from a bulk supply drum through heating tubes and back to the bulk supply drum and heating it to a cracking temperature in the heating tubes, maintaining a bed of finely divided solid material extending entirely across the path of the circulating charge of oil in the bulk supply drum, taking off vapors from the bulk supply drum under pressure, discharging pitch-laden oil from the circulating charge of oil in sufficient quantity to maintain said charge of oil substantially 55 constant, supplying to the circulating charge

of oil raw oil preheated by heat exchange with vapors taken off from the bulk supply drum and with discharged pitch-laden oil, and restricting the amount taken off as distillate not to exceed about 40% of the total raw oil supplied to the pressure still 60 including the initial charge.

8. An improved method of cracking hydrocarbon oils, which comprises circulating a 65 charge of oil in a pressure still from a bulk supply drum through heating tubes and back to the bulk supply drum and heating it to a cracking temperature in the heating tubes, maintaining a bed of finely divided solid material extending entirely across the path of the circulating charge of oil in the bulk supply drum, taking off vapors from the bulk supply drum under pressure and subjecting them to a refluxing operation, supplying raw oil to the refluxing operation 70 and returning reflux therefrom together with raw oil supplied thereto to the circulating charge of oil, discharging pitch-laden oil from the circulating charge of oil in sufficient quantity to maintain said charge of oil substantially constant, and preheating raw oil by heat exchange therewith, supplying raw oil so preheated to the circulating charge of oil, and restricting the amount taken off as distillate not to exceed about 45% of the total raw oil supplied to the pressure still 75 including the initial charge.

9. An improved method of cracking hydrocarbon oils, which comprises circulating a 80 charge of oil in a pressure still from a bulk supply drum through heating tubes and back to the bulk supply drum and heating it to a cracking temperature in the heating tubes, maintaining a bed of finely divided solid material extending entirely across the path of the circulating charge of oil in the bulk supply drum, taking off vapors from the bulk supply drum under pressure and subjecting them to a refluxing operation, supplying raw oil to the refluxing operation 85 and returning reflux therefrom together with raw oil supplied thereto to the circulating charge of oil, discharging pitch-laden oil from the circulating charge of oil in sufficient quantity to maintain said charge of oil substantially constant and preheating raw oil by heat exchange therewith, supplying raw oil so preheated to the circulating charge of oil, and restricting the amount taken off as distillate not to exceed about 40% of the total raw oil supplied to the pressure still 90 including the initial charge.

10. An improved method of cracking hydrocarbon oils, which comprises circulating a 95 charge of oil in a pressure still from a bulk supply drum through heating tubes and back to the bulk supply drum and heating it to a cracking temperature in the heating tubes, maintaining a bed of finely divided solid material extending entirely across the 100 path of the circulating charge of oil in the bulk supply drum, taking off vapors from the bulk supply drum under pressure and subjecting them to a refluxing operation, supplying raw oil to the refluxing operation 105 and returning reflux therefrom together with raw oil supplied thereto to the circulating charge of oil, discharging pitch-laden oil from the circulating charge of oil in sufficient quantity to maintain said charge of oil substantially constant and preheating raw oil by heat exchange therewith, supplying raw oil so preheated to the circulating charge of oil, and restricting the amount taken off as distillate not to exceed about 40% of the total raw oil supplied to the pressure still 110 including the initial charge.

11. An improved method of cracking hydrocarbon oils, which comprises circulating a 115 charge of oil in a pressure still from a bulk supply drum through heating tubes and back to the bulk supply drum and heating it to a cracking temperature in the heating tubes, maintaining a bed of finely divided solid material extending entirely across the path of the circulating charge of oil in the bulk supply drum, taking off vapors from the bulk supply drum under pressure, discharging pitch-laden oil from the circulating charge of oil in sufficient quantity to maintain said charge of oil substantially constant, supplying to the circulating charge

- path of the circulating charge of oil in the bulk supply drum, taking off vapors from the bulk supply drum under pressure, discharging pitch-laden oil from the circulating charge of oil in sufficient quantity to maintain said charge of oil substantially constant, supplying to the circulating charge of oil raw oil preheated by heat exchange with vapors taken off from the bulk supply drum and with discharged pitch-laden oil, and restricting the amount taken off as distillate not to exceed about 50% of the total raw oil supplied to the pressure still including the initial charge.
11. An improved method of cracking hydrocarbon oils, which comprises circulating a charge of oil in a pressure still from a bulk supply drum through heating tubes and back to the bulk supply drum and heating it to a cracking temperature in the heating tubes, maintaining a bed of finely divided solid material extending entirely across the path of the circulating charge of oil in the bulk supply drum, taking off vapors from the bulk supply drum under pressure, discharging pitch-laden oil from the circulating charge of oil, and supplying directly to the circulating charge of oil raw oil preheated by heat exchange with discharged pitch-laden oil.
12. An improved method of cracking hydrocarbon oils, which comprises circulating a charge of oil in a pressure still from a bulk supply drum through heating tubes and back to the bulk supply drum and heating it to a cracking temperature in the heating tubes, maintaining a bed of finely divided solid material extending entirely across the path of the circulating charge of oil in the bulk supply drum, taking off vapors from the bulk supply drum under pressure, discharging pitch-laden oil from the circulating charge of oil in sufficient quantity to maintain said charge of oil substantially constant, supplying to the circulating charge of oil raw oil preheated by heat exchange with discharged pitch-laden oil, and restricting the amount taken off as distillate not to exceed about 50% of the total raw oil supplied to the pressure still including the initial charge.
13. An improved method of cracking hydrocarbon oils, which comprises circulating a charge of oil in a pressure still from a bulk supply drum through heating tubes and back to the bulk supply drum and heating it to a cracking temperature in the heating tubes, maintaining a bed of finely divided solid material extending entirely across the path of the circulating charge of oil in the bulk supply drum, taking off vapors from the bulk supply drum under pressure, discharging pitch-laden oil from the circulating charge of oil in sufficient quantity to maintain said charge of oil substantially

constant, supplying to the circulating charge of oil raw oil preheated by heat exchange with discharged pitch-laden oil, and restricting the amount taken off as distillate not to exceed about 45% of the total raw oil supplied to the pressure still including the initial charge.
